GARMENT HANGER

Oliver R. Brekle, Birmingham, Ala., assignor to M&B Metal Products Co., a corporation of Delaware

Filed Apr. 18, 1968, Ser. No. 11,491

Term of patent 14 years

Int. Cl. D6—01

U.S. Cl. D80—8

FIG. 1 is a side elevational view showing the hook member formed integrally with a garment hanger;

FIG. 2 is an enlarged, fragmentary view showing the hook member; and

FIG. 3 is an end elevational view of FIG. 2.

The characteristic feature of my design resides in the specific configuration of the hook member in association with the garment hanger as shown.

I claim:

The ornamental design for a garment hanger, as shown and described.
